UNITED STATES PATENT OFFICE.

SOLOMON SCHWARZ, OF NEW YORK, N. Y., ASSIGNOR TO HYMAN GALLERT,
OF SAME PLACE.

BELT-HOLDER.

SPECIFICATION forming part of Letters Patent No. 626,101, dated May 30, 1899.

Application filed December 24, 1898. Serial No. 700,254. (No model.)

To all whom it may concern:

Be it known that I, SOLOMON SCHWARZ, of the city of New York, borough of Manhattan, in the county and State of New York, have invented a new and Improved Belt-Holder, of which the following is a full, clear, and exact description.

The object of the invention is to provide a new and improved belt-holder designed for holding a belt in position on trousers or other garments on which it is to be used, the holder being arranged to prevent the belt from slipping out of place and at the same time allow the necessary movements of the wearer's body without binding or injuring the garment or the belt.

The invention consists of novel features and parts and combinations of the same, as will be fully described hereinafter and then pointed out in the claim.

A practical embodiment of my invention is represented in the accompanying drawings, forming a part of this specification, in which similar characters of reference indicate corresponding parts in all the views.

Figure 1 is a perspective view of the improvement as applied to a man's belt. Fig. 2 is an enlarged sectional plan view of the same as applied on a garment, the section being taken on the line 2 2 of Fig. 1. Fig. 3 is an enlarged transverse section of the same on the line 3 3 in Fig. 1, and Fig. 4 is an inside view of the improvement as applied to a woman's belt.

On the inside of an ordinary belt A is sewed or otherwise secured a strip B of leather or other suitable material, and on this strip is arranged a longitudinally-extending guideway C, preferably formed of two parallel wires extending a suitable distance from the face of the strip B to penetrate with their ends the strip and be clenched on the back of the strip, as indicated in the drawings.

On the guideway C is mounted to slide longitudinally a holder D, preferably made of sheet metal in the form of a plate having turned-over top and bottom edges fitting on the wires of the guideway, so as to allow the plate to slide on the guideway. The plate is formed with a slot D' between the two wires forming the guideway, and said slot is en-

larged at one end for the entrance of a button and narrowed at the other end for the passage of the shank of the button. The top and bottom side walls of the slot, near the wide end thereof, are curved outwardly to form jaws D², adapted to engage the button-head, at the inside thereof, at the top and bottom, as is plainly indicated in Fig. 2. A tongue D³ extends longitudinally in the rear portion of the slot and from the wide end of said slot toward the narrow end thereof, and said tongue is formed with a hump or lug D⁴, adapted to snap into the central recess in a button E, as is plainly indicated in Fig. 2. The button E is of the usual kind and is secured to the garment F at the waistband, and for men's trousers the buttons generally used for the suspender-ends will answer the purpose. For ladies' waists separate buttons are employed at the rear ends of skirts; but in this case the holder D is placed in a vertical position, as indicated in Fig. 4, and has longitudinal movement on the guideways; otherwise the construction is exactly the same as above described in reference to Figs. 1, 2, and 3.

Only one holder is illustrated as attached to the belt; but it is evident that any desired number of such holders may be applied to the belt at places corresponding to the buttons on the garment.

In using the belt the operator simply slips the holder in a longitudinal direction to engage the button with the holder D in the manner above described, so that the jaws engage the edge of the button and prevent up-and-down movement thereof and a like movement of the belt, and the tongue D³ locks the button and holder together to prevent longitudinal movement of the holder, but allows the slide or holder to move longitudinally with the button on its guideways. Thus when the wearer bends his body he does not strain his trousers at the waistband, as the buttons with the slides or holders D can readily move in a longitudinal direction on the guideway C, and hence all undue strain on the buttons is prevented and at the same time said buttons remain in proper position on the garment.

The slide or holder D readily fits any but-

ton on a garment, as for specially-shaped buttons the slot in the holder can be changed accordingly.

Having thus fully described my invention, 5 I claim as new and desire to secure by Letters Patent—

A belt-holder, comprising a strip adapted to be secured to the inside of the belt, wires secured to said strip and forming longitudi-

nal guideways thereon, a holder in the form 10 of a plate and having bearings for sliding on said guideways, said plate being formed with a slot, jaws, and a tongue, all arranged substantially as shown and described.

SOLOMON SCHWARZ.
